UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

ASSOCIATING, CUTTING, AND FOLDING APPARATUS.

1,102,637.

Specification of Letters Patent.

Patented July 7, 1914.

Application filed August 15, 1910. Serial No. 577,252.

To all whom it may concern:

Be it known that I, HENRY F. BECHMAN, of Battle Creek, in the county of Calhoun and State of Michigan, have invented certain new and useful Improvements in Associating, Cutting, and Folding Apparatus; and I hereby declare that the following is a full, clear, and exact description thereof, reference being had to the accompanying drawings, which form part of this specification.

This invention is an improvement in folding mechanism for web printing machines, and its object is to enable newspapers of large size, or many pages, to be delivered and folded together without collecting.

The invention in brief comprises mechanism whereby the products of several web presses, or printing mechanisms, can be assembled, cut, and associated at one folder, and delivered folded together as one paper—but the products will be separately severed; which enables a larger number of pages printed on different webs to be assembled and delivered together in one section than it has been heretofore practical to do.

In my invention instead of attempting to assemble the webs of the different presses together and cut them all together, the webs from the several presses are separately severed, after they have been brought together at the associating point; and in this way I can assemble and sever a large number of pages without collecting, and simultaneously fold the associated pages in one folder. Thus I am able to cut and fold a larger product, or great number of pages, as one paper, for which there is now a great demand—without putting undue strain on the folding or cutting cylinders, or the cutting knives.

I will now describe the invention with reference to the accompanying drawings, which diagrammatically illustrate the means whereby the webs from two presses may be associated and folded together; but the invention is not limited to any particular make or number of presses, nor to any particular size or number of pages printed by each press. The parts of such presses and folders, as are well known, are conventionally illustrated in the drawings; but the following description and the drawings will

enable any one familiar with the art to construct and use the invention.

In said drawings—Figure 1 is a diagrammatical elevation of the delivery end of two web printing presses, and the novel means for associating, cutting, and folding their products. Fig. 2 is an enlarged elevation of the web cutting and folding mechanism.

In the drawings A and B designate the formers of folders located near the delivery ends of two web printing mechanisms of any suitable type, such for example as shown in my Patent #814,510 of March 6, 1906; and Reissue #13129 of July 12, 1910. A folding mechanism may be provided beneath each former, if desired, so that the webs from either press may be run to either folder. As such folding mechanisms could be duplicates I have shown one such folder at the apex of former A and means for directing the web (or webs) from former B to the folder beneath the former A. The same means would serve to direct webs from former A to a similar folder beneath the former B. The present invention resides more in the manner of and means for associating and severing the webs, than in the means for folding them after severing.

The folding and cutting devices as shown in drawings comprise a large novel cutting cylinder 1, provided with diametrically opposite cutting knives 1^a; and a female cutting and folding cylinder 2 adapted to contact with the cylinder 1 in severing the web (or webs) W fed thereto from former A. Said cylinder 2 is provided with tucker blades 2^a, and mechanism for operating them in the usual manner, so that said tucker blades will tuck the severed sheets between the folding rolls 4, 4, at the proper time and in the well understood manner. The cylinder 2 is also provided with pins 2^b, and their actuating mechanism, as usual; said pins being adapted to carry the leading end of the web (or webs) coming from former A from the point of severance by the blades 1^a to and beyond the rolls 4, to enable the blades 2^a to properly tuck the severed sheets between said rolls 4. At the upper side of cylinder 1, is an auxiliary female cutting cylinder 3 which is adapted to sever the web (or webs) w which is led thereto from the former B; said web (or webs) w coming from the press to and over

former B, then past the first fold rolls b , b , at the apex of former B, then to and over a guide 5, intermediate the formers, and thence to and between cylinders 1 and 3; 5 then it passes to and between the cylinders 1 and 2, where it is associated with the web (or webs) W coming from former A, and is carried therewith by pins 2^b in cylinder 2, to and over the folding rolls 4 between which, after severance, it is tucked, with the sheets severed from the web (or webs) W, by the blades 2^a. The knives, pins and tuckers may be of the usual construction and are so well understood that 10 no detailed description thereof is necessary.

In operation the parts are so arranged that the web (or group of webs) W is severed between the cylinders 1 and 2 at the point marked G, while the web (or group of webs) w is severed by and between the cylinders 1 and 3 at the point marked H. The cylinder 1 is provided with pins 1^b by 15 which the end of the web (or group of webs) w is carried from the point H over to the point G where it is associated with the web (or group of webs) W.

It will be seen that if each press is printing and delivering 18 pages on the respective webs (or sets of webs) W and w; that 20 the 18 pages from webs W would be severed at the point G, when the cutting points of cylinders 1 and 2 contact; and the 18 pages from webs w would be severed at the point H, when the cutting points of cylinders 1 and 3 come into contact. The webs W and w are thus severed separately, instead of together, and obviously less work and strain is put on the cutters than if it was attempted to cut all together; whereas it would be a 25 very difficult matter to cut such a large product at once by one set of knives as they could not properly penetrate such a great thickness of paper.

With the parts arranged as shown the webs w will be severed before webs W; that is, after the leading ends of the webs W, w, have both reached the point G, where the webs begin to assemble, the webs w will be severed at the point H about the time that 30 the leading ends of the webs come opposite the rolls 4;—or when the centers of the sheets to be folded have reached the point G; while the webs W are not severed until the leading ends of the webs have come 35 about diametrically opposite the point G; or the tail ends of the sheets on webs W reach the point G; and the cutters 1^a operate upon webs W through the cut in the webs w previously made by the action of 40 the cutting cylinders 1 and 3. In this way a large number of webs can be assembled, severed and the cut sheets delivered folded together as one paper, without collecting on the cylinder 2; as I simply associate the 45 products from one press, to wit, web (or

webs) W, with the product of the other press, to wit, the web (or webs) w, and discharge them both into the one folder. The pins 1^b carry the web (or webs) w after it is severed at the point H, over to the cutting point of the webs W at G, and then retract into the cylinder; and at this time the pins 2^b in cylinder 2 catch the ends of both the webs W and w and lead them on around cylinder 2 until web W is severed, whereupon the tucker blade 1^c delivers all the sheets to the folding rolls 4; in other words the pins 2^b lead the webs W, w to a point where the sheets severed therefrom can be folded properly between the rolls 4. It will 50 be seen that when the machine is properly arranged instead of both groups of webs, or 36 pages, having to be severed by one set of knives at the point G, only the web (or webs) W, or the product coming from the 55 former A, has to be severed at G; while the web (or webs) w, or the product coming from former B, is severed at the point H;—this enables the knives to sever the webs accurately and easily, and greatly lessens 60 the wear and strain on the cutting apparatus. It moreover does away with the necessity of "collecting" the sheets, thereby enhancing speed, and enables the papers from both webs (or groups of webs) to be associated and folded at one operation.

An additional web or webs, indicated at W' in Fig. 1, might be associated and folded with the webs W, w, if desired, by leading such webs from a third printing mechanism (not shown) to cylinder 2; a supplemental cutting cylinder 11, provided with a cutter blade 11^a, being arranged to co-act with cylinder 2 and sever the web (or webs) W' before they reach the point of association with webs W, w at G. The web (or webs) W in this case will be severed by the cutters on cylinder 1 as before described, said cutters operating through the prior cut in webs w, and at the point where web 110 W' has been already severed.

While it is not new, broadly speaking, to associate webs from one folder into another, or to carry a web from different presses to one, or the same, folding mechanism, it is 115 novel to sever the associated webs at separate points; and the specific arrangement of cutting and folding cylinders shown in the drawings is also novel and very useful.

What I claim is:

1. In associating and folding mechanism for printing presses, the combination of a folding cylinder and co-acting cutting cylinder, means for directing a web or webs between said cylinders to be cut thereby, means for directing another web or webs to and between said cylinders, and means co-acting with said cutting cylinder for separately severing the other web or webs independently of the said folding cylinder. 120 125 130 135 140 145 150 155 160 165 170 175 180

2. In associating and folding mechanism for printing presses, the combination of a folding cylinder, a cutting cylinder co-acting therewith, means for directing a web or webs between said cylinders to be cut thereby; means for directing a second web or group of webs to and between said cylinders, and a second cutting cylinder co-operating with the first cutting cylinder for severing the second web or webs. 70
3. In combination, folding rolls, a folding and cutting cylinder co-operating with said rolls, a cutting cylinder co-operating with said folding and cutting cylinder for severing a web or webs, means for directing a second web or webs to said cutting cylinder, and means co-acting with said cutting cylinder for severing the second web or webs independently of the first web or webs. 75
4. In combination, folding rolls, a folding and cutting cylinder co-operating with said rolls, a cutting cylinder co-operating with said folding and cutting cylinder for severing a web or webs; means for directing a second web or webs to said cutting cylinder, means in said cutting cylinder for directing the second web or webs to the point of association with the first web or webs, and means co-acting with said cutting cylinder for severing the second web or webs independently of the first web or webs. 80
5. In combination, a folding mechanism, a folding and cutting cylinder adapted to deliver associated sheets to said folding mechanism, a cutting cylinder co-acting with said cutting and folding cylinder, means for directing a web or webs between said cylinders to be severed thereby, means for directing another web or webs between said cylinders to be associated with the first web or webs, and means co-acting with said cutting cylinder to sever the other web or webs independently of the cutting and folding cylinder. 85
6. In delivery mechanism for printing presses, the combination of folding rolls, a folding and cutting cylinder adapted to deliver associated sheets to said folding rolls, a second cutting cylinder co-acting with said cutting and folding cylinder, means for directing a web or webs between said cylinders to be severed thereby, means for directing another web or webs between said cylinders to be associated with the first web or webs, and a third cutting cylinder co-acting with said second cylinder to sever the latter web or webs. 90
7. In combination, a folding mechanism, a folding and cutting cylinder provided with pins and tuckers adapted to deliver associated sheets to said folding mechanism; a second cutting cylinder co-acting with said cutting and folding cylinder, means for directing a web or webs between said cylinders to be severed thereby; pins in said cutting cylinder for directing another web or webs between said cylinders to be associated with the first web or webs; and a third cutting cylinder co-acting with said second cylinder to sever the latter web or webs. 95
8. Associating and folding mechanism comprising a folding cylinder, a male cutting cylinder co-acting therewith to sever a web, means for directing a plurality of webs to and between said cylinders; and a female cutting cylinder coacting with the male cutting cylinder for severing part of the associated webs independently of said folding cylinder. 100
9. In associating and folding mechanism for printing presses, the combination of a folding cylinder and co-acting cutting cylinder, means for directing a web between said cylinders to be cut thereby; means for directing another web to and between said cylinders, and means co-acting with said cutting cylinder for separately severing the latter web; means for directing a third web between the cutting and folding cylinders, and means co-operating with the folding cylinder for cutting the third web independently of the cutting cylinder. 105
10. Associating and folding mechanism for printing presses, comprising a cutting and folding cylinder, a male cutting cylinder co-acting therewith, means for directing a web between said cylinders to be cut thereby; means for directing another web to and between said cylinders; means co-acting with said male cutting cylinder for separately severing the latter web independently of said folding cylinder; means for directing a third web between the cutting and folding cylinders, and a second male cutting cylinder co-operating with the folding cylinder for cutting the third web independently of the first cutting cylinder. 110
11. In folding and cutting mechanism for web printing presses and the like, the combination of folding rolls, a folding cylinder, means for directing a plurality of webs to said folding cylinder to be associated and delivered thereby to the folding rolls, and means whereby said webs after being associated are severed at different times, and at different points. 115
12. In folding and cutting mechanism, the combination of folding rolls, a folding cylinder provided with collecting pins and tucker blades, means for directing a plurality of webs to said folding cylinder to be associated and delivered thereby to the folding rolls, and means whereby said webs after being associated are severed at separate points, and at different times, but prior to delivery to said rolls. 120
13. In folding mechanism, a cutting and folding cylinder, means for directing a plurality of webs to such cylinder, and a plurality of cutting cylinders co-acting with 130

- said cutting and folding cylinder for severing said webs at separate points and at different times after association thereof but prior to folding same.
- 5 14. In folding mechanism, means for associating a plurality of webs or groups of webs and directing them to such folding mechanism, a single cutting cylinder, and a plurality of cutting members coöperating therewith to sever said webs or groups of webs separately and at different times after such webs or groups of webs are associated in such mechanism, but prior to folding thereof.
- 10 15. Web associating and folding mechanism, comprising a folding and cutting roll.

a cutting roll co-acting therewith, means for directing a web thereto to be cut thereby; a third roll having a cutting member co-acting with the folding and cutting roll, and means for directing a web between said rolls to be cut thereby; said rolls severing the webs separately and at different times after association and prior to folding.

In testimony that I claim the foregoing as 25 my own, I affix my signature in presence of two witnesses.

HENRY F. BECHMAN.
